UNITED STATES PATENT OFFICE

96,290

DESIGN FOR A LACE

William H. Woodhouse, Hightstown, N. J., assignor to Gehring, Solomon & Birnbaum, Inc., New York, N. Y., a corporation of New York

Application May 16, 1935, Serial No. 56,860

Term of patent 3½ years

To all whom it may concern:

Be it known that I, William H. Woodhouse, a citizen of the United States, residing at Hightstown, in the county of Mercer and State of New Jersey, have invented a certain new, original, and ornamental Design for a Lace, of which the following is a specification, reference being had to the accompanying drawing, forming a part thereof.

The single figure in the drawing is a plan view of a lace showing one repeat of the design which is repeated at regular intervals.

I claim:

The ornamental design for a lace, as shown and described.

WILLIAM H. WOODHOUSE.
